UNITED STATES PATENT OFFICE.

JOHN W. WEDDEL, HARVEY JEWETT, WILLIAM L. TAYLOR, AND DANIEL A. BELLIS, OF OREGON, ILLINOIS.

MOTOR FOR OPERATING PUMPS.

SPECIFICATION forming part of Letters Patent No. 609,565, dated August 23, 1898.

Application filed August 2, 1897. Serial No. 646,737. (No model.)

To all whom it may concern:

Be it known that we, JOHN W. WEDDEL, HARVEY JEWETT, WILLIAM L. TAYLOR, and DANIEL A. BELLIS, citizens of the United States of America, residing at Oregon, in the county of Ogle and State of Illinois, have invented certain new and useful Improvements in Motors for Operating Pumps, of which the following is a specification.

10 The principal object of this invention is to provide a simple weight-actuated mechanism which may be used for operating any suitable machine, though it is especially intended for operating an ordinary pump and is shown 15 and described herein in working connection with a pump.

The invention is fully described and explained in this specification and shown in the accompanying drawings, in which—

20 Figure 1 is a side elevation of a mechanism embodying our improvements and showing the same in working relation to a pump. Fig. 2 is a top plan of the entire mechanism shown in Fig. 1. Fig. 3 is a horizontal section through the line 3 3, Fig. 1, the view being downward. Fig. 4 is a front elevation of the entire mechanism shown in Fig. 1, the view being in the direction indicated by the arrow α , Fig. 1. Fig. 5 is a view partly in vertical section and partly in side elevation, the plane of section being through the line 5 5, Fig. 4, and the view being in the direction indicated by the arrow α' , Fig. 4. Fig. 6 is a vertical section through the line 6 6, 35 Fig. 5, the view being in the direction indicated by the arrow α^2 , Fig. 5. Fig. 7 is a horizontal section through the line 7 7, Fig. 5, the view being downward. Fig. 8 is an enlarged side elevation of the pump, the pump-lever, 40 and the crank-plate by which the lever is operated; and Fig. 9 is a horizontal section through the line 9 9, Fig. 8, the view being downward.

In the views, A A A' A' A² A² are the preferably tubular vertical standards of a frame supporting the weight-actuated gearing of our operating mechanism, one set of standards A A' A² being arranged at one side of the frame and the other set in corresponding 45 positions at the opposite side thereof and all these standards being joined at their lower

ends by horizontal tubes B B B B, connected with the standards by suitable unions, as hereinafter set forth. The pair of standards A A at the front of the frame are shorter 55 than the standards A' A², and their upper ends are connected with the upper ends of the standards A' A' by oblique tubes A³ A³. Horizontal connecting-tubes B' B' at the level of the upper ends of the standards A A join 60 all the standards, as clearly shown in the drawings, and horizontal tubes B² B² at the upper end of the frame join the ends of the standards A' A² and the oblique tubes A³ A³. The standards may be connected with the 65 horizontal tubes in any desired manner; but we prefer to use such unions as are illustrated in the drawings, the union at each angle of the base being formed with a vertical socket to receive the vertical standard and two horizontal 70 sockets at right angles to each other to receive the tubes B B, and the union at each of the other joints being so constructed as to suitably receive the intersecting members.

On the front standards A A are secured two 75 preferably adjustable thimbles K K, bearing projecting lugs K' K', which are bored horizontally to form the bearings of a horizontal shaft C, and on the two horizontal tubes B' B' are mounted similar adjustable bearings 80 bored horizontally to receive three suitably-placed horizontal shafts C' C² C³, whose relation to each other is clearly illustrated in Fig. 5. The horizontal shaft C is provided at one 85 end with a crank for its rotation and has about midway of its length a windlass W, adapted to receive a rope R, passing over a fixed pulley P at the top of the frame, and a movable pulley P', supporting a weight W'. The pulleys P P' may each have any desired 90 manner of sheaves for varying the relative movement of the windlass and weight; but it is evident that the rotation of the windlass in one direction will raise the weight, and the fall of the weight, on the other hand, will rotate the windlass and shaft C in the opposite direction. The shaft C also carries a rigidly- 95 attached sprocket-wheel D, which is connected, by means of a chain E, with a second sprocket-wheel D', rigidly mounted on the 100 shaft C', and on the shaft C' is rigidly mounted a ratchet-plate F, of which the teeth are

adapted to engage a pawl F', pivoted on a gear-wheel G, which is loosely mounted on the same shaft C'. The gear G engages a pinion G', rigidly mounted on the shaft C², 5 and a gear-wheel G², also rigidly mounted on the shaft C², engages a second pinion G³, rigidly mounted on the shaft C³. The shaft C³ is also provided with a sprocket-wheel D², rigidly mounted on one end of the shaft which 10 projects outside the frame, and this sprocket-wheel is connected, by means of a chain E', with a sprocket-wheel D³, loosely mounted on a similarly-projecting end of the shaft C and rigidly connected with a crank-plate H, bearing 15 a crank-pin and a roller r. This roller lies within a longitudinal slot S in the free end of a pump-lever I, adapted to operate the pump-rod P³ of a pump of the usual general construction. In this pump, however, of 20 which the operating mechanism is shown in detail in Fig. 8, the end of the pump-lever is pivoted to the pump-rod in the usual manner; but the lever is formed with a downwardly-convex bend i, which rests upon a roller r', 25 supported in the pump-head. This roller-support permits necessary longitudinal movement of the lever to accommodate it to the changes of position of the pump-rod, and forms a practically frictionless and very simple support of the pump-lever.

From the foregoing description of our illustrated mechanism it is evident that the rotation of the shaft C and drum W in the direction indicated by the arrow on the shaft in 30 Fig. 5 must wind the rope upon the drum, and thereby raise the weight W', and that by this movement of the drum and the shaft C the shaft C' must be rotated in the same direction, carrying the ratchet-wheel F with it 35 in the direction indicated by the arrow on the hub of the ratchet-wheel in the same figure. In this movement the teeth of the ratchet-wheel successively pass the point of the pawl F' without affecting the train of gearing; but 40 as soon as the winding force is removed from the shaft C the weight tends to rotate it in the opposite direction, thereby reversing the movement of the ratchet-wheel F and communicating its new movement through the 45 pawl F', to the train of gearing G G' G² G³ and the shaft C³, on which the pinion G³ is mounted. This rotation of the shaft C³ is evidently communicated through the sprocket-wheels D² D³ and chain E' to the crank-plate H, and 50 the rotation of the crank-plate with its crank pin and roller r must evidently oscillate the pump-lever I and operate the pump-rod P³. The whole mechanism forms a simple and practical means of operating a pump and may 55 be used either independently or as supplementing the operation of a windmill, the weight-actuated motor being brought into use when the windmill is inoperative by reason of lack of necessary wind.

60 It is sometimes desirable to stop the operation of the motor before the weight has reached its lowest limit of movement and com-

pletely expended its stored-up energy, and for this reason it is advisable to provide some convenient means for locking some element 70 of the mechanism against rotation. A very simple means for this purpose is shown in Fig. 7 and consists simply in making the crank L reversible on the squared end of the shaft, bringing its handle L' into the position shown 75 in Fig. 7, in which the partial rotation of the shaft must bring it into contact with the standard A of the frame, thereby stopping the shaft C and arresting the movement of the entire mechanism. 80

The four standards A A' A² A³ of the frame constitute a sort of skeleton shaft in which the weight W' may be supported in any desired manner; but we prefer the construction shown in Fig. 2, in which the top of the shaft 85 is provided with intersecting tubes B⁸ B³, the weight being suspended from the intersection of these tubes, so as to be held always central with reference to the four standards. The adjustable shaft-bearings K K' may evidently 90 be useful and convenient elements of a mechanism of any kind comprising different shafts whose relative positions may advantageously be changed; but they are particularly desirable when used as supports for shafts connected by sprocket wheels and chains—as, for instance, the shafts C C' in the mechanism shown and described herein.

The principal use of a motor such as we have shown will be found on farms and in 100 other places where repairs cannot readily be made, and as the element of the machine most liable to breakage is the chain we have found it very desirable to make the shaft C conveniently adjustable upon the standards A A, in 105 order to compensate for any loss of length of the chain through the breakage of one of its links. With the shaft thus adjustable it is only necessary to take out a broken link, move the shaft C upward a sufficient distance to 110 permit the coupling of the ends of the chain, and then make the coupling, when the machine will be in working order the same as if the break had not occurred. In Figs. 1, 2, and 4 we have shown a fly-wheel W², which is 115 preferably used in this motor and is mounted upon the shaft C³. This wheel is of sufficient size and weight to give an even and steady motion to the pump which the motor is operating. 120

Having now described and explained our invention, what we claim as new, and desire to secure by Letters Patent, is—

1. The combination with a suitable supporting-frame of a shaft mounted in the frame 125 and provided with a rigidly-mounted drum, a rope attached to said drum and passing over suitable pulleys, a weight attached to the free end of the said rope, a crank-plate mounted loosely on said drum-shaft and free to rotate 130 independently thereof, a train of gearing interposed between the drum-shaft and said crank-plate and means for connecting the crank-plate with a pump-lever, the rotation

of the drum-shaft in one direction being adapted to raise the weight and its rotation in the opposite direction being transmitted through said gearing to said crank-plate whereby the latter may be rotated and thereby operate the pump-lever.

2. The combination with the frame comprising substantially, the standards, A, A, and the higher standards, A', A', A², A², the oblique members, A³, A³, the horizontal members, B, B, B', B', B², B², connecting said standards, the standards, A', A², being arranged to form a skeleton shaft, and the weight-supporting members, B³, of the pulley, P, suspended from said supporting members in the center of the shaft, the weight, W', the pulley, P', suspending said weight, the rope, R, passing over the pulley, P, and around the pulley, P', the shaft, C, and drum, W, mounted thereon, the crank-plate loosely mounted on said shaft and the gearing constructed substantially as described and interposed between the shaft, C, and the crank-plate, the rope, R, being fastened at one end to the drum and at the opposite end to the housing of the pulley, P, whereby the rotation of the shaft, C, in one direction may raise the weight, W', and its rotation in the opposite direction may

be transmitted through the gearing to the crank-plate.

3. The combination with the frame, the shaft, C, having the drum, W, and the rope attached to the frame and passing over suitable pulleys to a weight, W', of the shaft, C', connected substantially as shown and described with the shaft, C, the ratchet-wheel, F, mounted rigidly on the shaft, C', the gear-wheel, G, mounted loosely on the shaft, C', and provided with the pawl, F', adapted to engage the ratchet-wheel, F, the crank-plate, H, mounted loosely on the shaft, C, and gearing interposed between the gear-wheel G and the crank-plate, H, whereby the rotation of the gear-wheel, G, may be transmitted to the crank-plate.

In witness whereof we have hereunto set our hands, this 22d day of July, A. D. 1897, at Oregon, in the county of Ogle and State of Illinois.
